UNITED STATES PATENT OFFICE.

MARK DEAN, OF BOSTON, MASSACHUSETTS, ASSIGNOR TO THE HERENDEEN MANUFACTURING COMPANY, OF GENEVA, NEW YORK.

STEAM AND HOT-WATER BOILER.

No. 816,567.

Specification of Letters Patent.

Patented April 3, 1906.

Application filed December 30, 1897. Serial No. 664,600.

To all whom it may concern:

Be it known that I, MARK DEAN, a citizen of the United States, residing at Boston, in the county of Suffolk and State of Massachusetts, have invented certain new and useful Improvements in Steam and Hot-Water Boilers, of which the following is a specification.

This invention relates to steam and hot-water boilers for heating apartments and buildings, and it relates more particularly, first, to a novel construction whereby the heat is diffused and deflected by non-inflammable removable bars vertically suspended in the smoke or flame passage in opposite sides of the boiler, such bars, in connection with the peculiarly-constructed adjacent parts of the boiler, serving to take the flames and products of combustion from opposite sides of the fire-pot between vertical waterways, split them into vertical sheets of flame, cause such sheets of flame to impinge against vertical waterways at substantially right angles thereto, from which they are deflected and move horizontally to the outlet or smoke flue; second, to improved means whereby any desired number of the series of grates may be shaken or cleared of ashes, so as to confine the live fire to as small a portion of the entire grate-surface as may be desired, the shaking of all the grates or of any number of them being done by a single operation; third, to an improved construction whereby the shaker may be detached from the grates without the employment of any connecting mechanism in the ash-pit, all the mechanism for the purpose being outside the ash-pit and above the level of the grate; fourth, to an improved combination and arrangement of parts in the construction of the dampers whereby the draft-damper and check-damper may be more exactly, efficiently, and simply regulated and operated and provision made for carrying off the dust and rising ashes into and up the flue when the grate has been shaken, and to other novel constructions and arrangements of parts whereby the boiler and its parts are rendered more durable, its efficiency enhanced, and the proportion of heat obtained is increased, all substantially as fully described below and illustrated in the accompanying drawings, in which—

Figure 1 is a side elevation of my improved boiler. Fig. 2 is a front elevation of the

same. Fig. 3 is a longitudinal vertical section. Fig. 4 is a horizontal section taken on line 4, Fig. 3, a small portion being represented as having been broken out. Fig. 5 is a vertical section taken on line 5, Fig. 4. 60 Fig. 6 is an elevation of a portion of the grate mechanism. Fig. 7 is a horizontal section of the same. Fig. 8 is a part vertical section and part elevation of the same. Fig. 9 is a cross-section taken on line 9, Fig. 8. Fig. 10 65 is a cross-section taken on line 10, Fig. 8. Fig. 11 is a rear elevation of the boiler. Figs. 12 and 13 are enlarged vertical sections of the smoke-flue and dampers with the latter in different positions. 70

Similar letters of reference indicate corresponding parts.

A represents the front wall of the boiler or heater, and A' the front wall of the ash-pit, said walls being provided with the ordinary doors a, a', and a''.

A'' represents the side walls of the ash-pit, provided with suitable doors a''', and A''' is the rear wall of the ash-pit, provided with the passage b, opening into the rear flue or smoke-flue B, which is described below.

c represents a series of rotative grates.

The front wall A is also the front wall of a water-space formed by the dome D, which extends down into the water-legs D' on opposite sides of the door a, such water-legs having their inner walls D'' in shape to conform to the shape of the grate, as shown in Fig. 4, and being connected near their lower ends by the horizontal waterway D'''. (See Fig. 3.) 85 At the rear end of the boiler is a dome E, whose rear wall A'''' constitutes the rear wall of the boiler, such dome being provided with water-legs E', which extend inward to the central horizontal smoke-passage f, which 90 opens into the smoke-flue B. Below this passage f the water-legs E' are connected by a waterway E''. Between the domes D and E is a series of domes F, from each of which two pairs of parallel vertical water-legs extend, 100 one pair on each side of the fire-pot. Each outer water-leg F' is connected at its lower end with the lower end of the inner water-leg F'' by a waterway F''', and these water-legs are all supported by the base C, which 105 sustains the grates c. (See Figs. 1, 3, 4, and 5.) The outer walls of the outer water-legs F' are preferably convex in horizontal section, as shown, and the walls e of the inner water-legs F'' are angle-shaped, as shown in Fig. 4. 110

in order to conform and hug closely to the ends of the grates *c*. The walls *e' e''*, Figs. 4 and 5, are straight and vertical, and thereby constitute a horizontal and straight passage *H* between them. The walls *e'''* of the water-legs *F''* are so formed as to provide vertical passages *g* between them, which enlarge at their upper ends into the flame-passages *g'*. The inner water-legs *F''* of the dome *F* next to the rear dome *E* are extended, as shown in Fig. 4, so as to provide a greater heating-surface and also project over the fire-pot by means of the peculiar form shown at *F'''*, and their lower connection *F'''*, Fig. 3, is larger than those of the other water-legs, so as to present a large heating-surface at the rear of the fire-pot. These domes are formed to open into each other and connect, as shown in Fig. 3, by means of the passages *D''''* Fig. 5. Each dome, except the front one, has its front side around said passage formed into the circular male boss *d*, and each dome, except the rear one, has its rear side formed into the angle-shaped female boss *d'*. Between the extreme outer end of each boss *d* and the rear side of the angle portion of each boss *d'* is a gasket or washer *d''* of pliable material. By this means the domes are formed with joints consisting practically of parallel and fitting metallic plates, while rust is prevented from forming on the interior of the ring-shaped or circular joints and such joints rendered perfectly tight by means of the gaskets, which are in contact with the domes only at the points where the extreme ends of the bosses *d* abut against the inner ends of the bosses *d'*. The sections or domes are held together by means of horizontal rods *g''*, which are inclosed in a series of cast pipes or tubes *g'''*, one set of such pipes being inclosed within each section or dome and the rods *g''* extending through all the sections, which are held together by means of nuts placed on the outer ends of said bolts or rods. By this means said rods are prevented from rust. The opening *h*, Figs. 2, 3, and 11, is that through which the water or steam is distributed throughout the building or apartment to be heated. As will readily be seen, the water and steam circulate freely through these water-legs, connecting-waterways, and domes.

Suspended from the under sides or walls of the domes *F* centrally within the passages *H* and between the upright walls *e'* and *e''* are the non-inflammable removable bars or deflectors *K*, preferably of diamond shape in cross-section. When the flames and products of combustion leave the fire-pot, they sweep outwardly horizontally through the passages *g g'* between the water-legs *F''* into the horizontal passages *H*. The first movement of these flames as they enter the passages *H* is to impinge at substantially right angles against the inner walls *e'* of the outer

water-legs *F'*. Thence they are drawn rearward and are split and deflected by the deflectors *K*, so that they drive against both walls *e'* and *e''* on opposite sides of the passage *H*, and are thence drawn horizontally inward through the passage *K'* and out through the smoke-passage *f* into the smoke-flue *B*. Thus two opposite sheets of vertical flame pass horizontally through the passages *H*, the sheets of flame being always vertical and their movement being always horizontal. It is evident that all of the following walls—viz., *D''', e', e'', e'''*, *F'''*, the wall of the smoke-passage *D'''*, those of the smoke-passages *F''* and *E'*, and those of the water-legs *E''*—are brought into direct contact with the flames and products of combustion. It will be noticed that the deflectors *K* are of varying sizes, the largest being near the front ends of the passage *H* and the smallest near the rear ends. Inasmuch as the flames and products of combustion entering the passages *H* through the passages *g g'* must necessarily accumulate or be greater in bulk toward the rear ends of the passages, it is deemed advisable that the deflectors should occupy less space and afford less resistance as the flames reach the rear portions of said passages. Moreover, the deflectors not only serve to diffuse the heat, but may operate to regulate the size of the smoke-opening, and thereby overcome excessive draft.

The grates *c* at one end are formed with the squared extensions or bars *c'*, Figs. 5, 8, and 10, which extend into correspondingly-shaped sockets *J*, having their bearings in the base *A''*, as shown, and formed at their outer ends with the cranks *J'*, whose free ends *J''* are bent diagonally, as shown in Figs. 6 and 7, and provided with the squared sockets *J'''*. The sockets or tubular connections *J* are provided with lugs *I*, which when said connections are inserted are slipped through the correspondingly-shaped slots *I'* in the side wall *A''*, Fig. 6, and when the cranks *J''* are swung up said lugs lie in the slots *I'*, Fig. 9, behind the side plate *A''*. Thus connection is made with the grates without the use of bolts or cotters under the grates, thereby preventing the annoyance which arises from such devices rusting in place and rendering difficult the removal of the shaker. These cranks or operating-arms *J'* are provided on alternate sides with openings into which pins or bolts *l* can be placed, said bolts being adapted to extend through corresponding openings in the downward projections *L''* from the two horizontal portions *L* and *L'* of a double connecting-bar—i. e., the first, third, and fifth grates are connected by the pins *l* to the bar *L'* and the second and fourth grates by the pins *l* to the bar *L*. It is evident, therefore, that if an ordinary shaker is applied to the socket *J'''* in one of the cranks or arms *J'* which is connected with the bar *L* all the grates which

are connected with that bar will be simultaneously shaken, while if the shaker be applied to the socket in a crank or arm which is connected with the bar L' the grates connected with the last-named bar will be shaken. Thus one-half of the grates are shaken by one bar and the other half by the other bar. It is evident that by removing one or more of the bolts *l* as many or as few of the grates 5 may be shaken as desired, for by providing openings for the bolts *l* in all the cranks or arms J' such cranks or arms may be connected with the downward extensions L'' on either of the bars L L'. The upper surfaces 10 of these bars are provided with suitable notches *m*, and a support *n* is rigidly secured at *n'* to a bracket *n''*, extending from the side or base A'', the upper end of said support extending between the bars L L'. Pivotally secured at *n''*, Fig. 6, to said support 15 are the locking-bars N N', Figs. 4, 6, and 7, whose outer ends are bent into the latches N' N'' and whose rear ends are sufficiently long or heavy to hold the latches up if they are 20 swung back out of engagement with the notches *m* or allow them to lie in said notches if they are swung down into such engagement. Thus either or both of the bars L L' may be locked, and hence the grates with 25 30 which such locked bar is connected be rendered immovable. In Figs. 4, 6, and 7 one of the bars is represented as locked and the other as free to be operated. By means of this contrivance the user of the boiler can run 35 the fire upon whatever portion of the grate-bars he deems advisable. As will readily be seen, the connections between the grates and the shaker are exceedingly simple and are practically all outside the ash-pit and in 40 the main above the level of the grate, thus doing away with bolts or coppers, which are apt to rust in place.

The rear wall B' of the smoke-flue B is provided with the horizontal draft-openings B'', 45 as indicated in Figs. 3, 11, 12, and 13, and with the vertical slideway B''', within which is the damper P, provided with the draft-openings P' and check-draft openings P''. This damper slides vertically and is operated automatically by the damper-regulator R, Figs. 50 3 and 11, consisting of a diaphragm and case operated automatically by steam through the means of the pipe R, Figs. 4 and 11, in the usual manner. A rotative damper S is hung centrally within the smoke-flue B and 55 operated by the handle S', which is fixed to the shaft of the damper outside of the flue at right angles with said damper, Figs. 1, 12, and 13. The normal position of the parts 60 when the sliding damper P is down is indicated in Figs. 1, 3, 4, 11, and 12. In this position the damper S is closed and the draft-openings P' in the damper P coincide with the openings B'' in the rear wall of the smoke-flue 65 below the damper S. When the draft is

to be checked, the pressure of steam in the regulator R lifts the damper P until the openings B'' below the damper S are closed; but the openings P'' coincide with the openings B'' above the damper S. The damper P is 70 provided with a projecting arm T, which extends rearward and toward the left and beyond the edge of the said damper, so that it projects over the path of the handle S' in case said handle is swung up. Now supposing 75 the damper P to be down, as in Fig. 12, before shaking the grates the arm S' is swung up into the position indicated in Fig. 13, so as to leave the flue open to the passage of the rising ashes and dust. This causes the handle S' to engage the projecting arm T and lift the damper P just enough to close the openings B'' below the damper S, but not enough to open the openings B'' above the damper S. Thus the rear wall of the smoke-flue B is 80 closed and the dust and ashes drawn up through the flue without leaking or sifting out through the sliding damper while the grates are being shaken. When the arm S' of the damper is swung up, it is held in such 85 90 position by one of the teeth U, Figs. 1 and 4.

In order that the deflectors K may be removed, the passages H are extended through the front wall A, access being had by means of doors V. 95

The passage W, Fig. 3, is utilized as a direct draft when building a fire.

It will be observed by reference to Figs. 3 and 4 that the generator comprises upright sections arranged one in advance of the other, 100 a number of the sections being each formed with substantially upright chambers F' F'' at opposite sides of the combustion-chamber, said upright chambers being connected at their upper ends and provided with flues H 105 extending through their front and rear faces, and fire-passages projecting laterally from the flues or communicating laterally with said flues for conducting the products of combustion to the flues and one of the sections being provided with flues extending through its front and rear faces and alined with the before-mentioned flues, fire-passages communicating laterally with the inner sides of its flues, and a water-containing chamber arranged at the rear of the fire-passages for forming the rear wall of the combustion-chamber. 110 115

Having thus fully described my invention, what I claim, and desire to secure by Letters 120 Patent, is—

1. In a steam or hot-water boiler, in combination with the vertical water-passages F'' set on opposite sides of the fire-pot and separated by vertical flame-spaces; the vertical water-passages F' provided with the straight horizontal sides e' facing inward toward the fire-pot and at right angles with said flame-passages, the horizontal flame-passages H located between said passages F'' and F', and 125 130

horizontal passages connecting the passages H with the smoke-flue, whereby the flames are drawn in vertical sheets horizontally outward from the opposite sides of the fire-pot 5 or combustion-chamber between the water-passages F'' and impinge horizontally against the walls e' of the water-passages F' at right angles to said walls and are thence drawn horizontally through the passages H to the smoke-flue, substantially as described.

2. In a steam or hot-water boiler, in combination with two rows of vertical water-passages set between the fire-pot and the side of the boiler whereby a horizontal passage H is 15 formed between said rows; a number of non-inflammable heat-deflecting bars suspended within said passage H, whereby the flames entering said passage are split and deflected against the walls of the water-passages adjoining the passage H, substantially as set forth.

3. In a steam or hot-water boiler, in combination with two rows of vertical water-passages set between the fire-pot and the side of the boiler whereby a horizontal passage H is 25 formed between said rows; the non-inflammable heat-deflecting bars K thicker at their centers than at their front edges and suspended within said passage H, whereby the flames entering said passage are split and deflected against the walls of the water-passages adjoining the passage H, substantially as described.

4. In a steam or hot-water boiler, in combination with two rows of vertical water-passages set between the fire-pot and the side of the boiler whereby a horizontal passage H is 35 formed between said rows; the series of non-inflammable heat-deflecting bars varying in thickness and with the thickest bar nearest the front wall of the boiler and said bars growing gradually thinner toward the rear wall thereof, said bars being suspended within said passage H, whereby the flames entering said passage are split and deflected against the walls of the water-passages adjoining the passage H, substantially as set forth.

5. In a steam or hot-water boiler, in combination, the domes D, F, provided with the 40 water passages or legs D', F', F'' extending down on opposite sides of the fire-pot as described, each dome F being provided with four water-legs F', F'' two of which are on each side of the fire-pot whereby horizontal 45 passages H are formed between each series of pairs of water-legs, the rearmost of the domes F being formed with the water-legs F'' extending at their inner ends forward over the rear gate at F'''; and the dome E provided with the broad inwardly-extending water-leg E', all substantially as and for the purpose set forth.

6. A generator comprising upright sections arranged one in advance of the other, a number of the sections being each formed with 55 substantially upright chambers at opposite sides of the combustion-chamber, connected at their upper ends, said chambers being provided with flues extending through their front and rear faces, and fire-passages communicating laterally with the flues for conducting the products of combustion thereto.

7. A generator comprising upright sections arranged one in advance of the other, a number of the sections being each formed with 70 substantially upright chambers at opposite sides of the combustion-chamber, connected at their upper ends, said chambers being provided with elongated upright flues extending through their front and rear faces at opposite 75 sides of the combustion-chamber, and having their front and rear faces formed with fire-passages communicating laterally with the inner sides of the flues through the upright sides of the combustion-chamber for conducting the products of combustion to said flues.

8. A generator comprising upright sections arranged one in advance of the other, a number of the sections being each formed with substantially upright chambers at opposite 85 sides of the combustion-chamber, connected at their upper ends, said chambers being provided with flues extending through their front and rear faces, and one of the sections being provided with flues extending through 90 its front and rear faces and alined with the former flues, fire-passages communicating laterally with the inner sides of the flues, and a water-containing chamber arranged at the rear of the fire-passages for forming the rear 95 wall of the combustion-chamber.

9. A generator comprising upright sections arranged one in advance of the other, a number of the sections being each formed with substantially upright chambers at opposite 105 sides of the combustion-chamber, connected at their upper ends, said chambers being provided with flues extending through their front and rear faces, and fire-passages communicating laterally with the flues for conducting the products of combustion thereto, and one of the sections being provided with flues extending through 110 its front and rear faces and alined with the former flues, fire-passages communicating laterally with the inner sides of the flues and a water-containing chamber arranged at the rear of the fire-passages for forming the rear wall of the combustion-chamber.

MARK DEAN.
